REFRIGERATION SYSTEM

Filed March 14, 1932

Fig. 1

The diagram illustrates a refrigeration system with the following components and their labels:

- COOLING FLUID** enters the system at the top left.
- COMP. AIR** enters the system at the top right.
- COOLED FLUID** exits the system at the middle right.
- HEATING FLUID** enters the system at the bottom right.

Key components and their labels include:

- 17: Vertical pipe section.
- 18: Coiled tube assembly.
- 19: Vertical pipe section.
- 21: Vertical pipe section.
- 22: Pump assembly.
- 23: Vertical pipe section.
- 24: Coiled tube assembly.
- 25: Coiled tube assembly.
- 26: Vertical pipe section.
- 27: Vertical pipe section.
- 28: Valve assembly.
- 29: Vertical pipe section.
- 30: Valve assembly.
- 34: Vertical pipe section.
- 35: Vertical pipe section.
- 36: Valve assembly.
- 37: Vertical pipe section.
- 38: Valve assembly.
- 39: Valve assembly.
- 41: Vertical pipe section.
- 42: Valve assembly.
- 44: Vertical pipe section.
- 45: Vertical pipe section.
- 46: Valve assembly.
- 47: Valve assembly.
- 48: Valve assembly.
- 49: Valve assembly.

INVENTOR.
BY FLOYD L. KALLAM
HENRY N. YOUNG
ATTORNEY.

UNITED STATES PATENT OFFICE

2,035,814

REFRIGERATION SYSTEM

Floyd L. Kallam, South Gate, Calif.

Application March 14, 1932, Serial No. 598,551

6 Claims. (Cl. 62—115)

The invention relates to a refrigeration system utilizing the principle of jet compression in a closed circuit.

An object of the invention is to provide an improved refrigeration system of the character described wherein but one fluid is utilized in the refrigerant circuit.

Another object of the invention is to provide a refrigeration system wherein the operating pressures are arranged to be relatively high, thereby providing a particularly high degree of operative efficiency for the system.

A further object is to provide a refrigeration system adapted for the use therein of a refrigerant fluid lacking a fixed boiling point.

A more specific object is to provide an improved refrigeration system which, while of general application, is particularly adapted for use in connection with a plant for refining mineral oils, the particular adaptation arising through the possible use in the system of both a product and heat which are normally wasted in such a plant.

The invention possesses other objects and features of advantage, some of which, with the foregoing, will be set forth or be apparent in the following description of a typical embodiment of the invention which is illustrated in the accompanying drawing, in which,

Figure 1 is a diagrammatic showing of a system embodying the present invention.

Figure 2 is an enlarged sectional view of a jet compressor element of the system.

As particularly illustrated, the features of the present invention are incorporated in a refrigeration system wherein a boiler 5, a jet compressor 6, condenser 7, pump 8 and evaporator 9 comprise the principal operative elements, said elements connected to provide a closed circuit for a refrigerant 11 which is alternately gasified and liquefied as it circulates through the system.

The boiler 5 may be of any conventional type, but for a reason to be hereinafter brought out the present boiler is disclosed as a heat exchanger wherein heated fluid which is to provide the heat thereat is supplied through connecting pipes 12 of a circuit which is independent of the refrigerant circuit. A pipe 13 conducts gasified refrigerant from the boiler to the jet compressor 6, and means are preferably provided to insure constant temperature and pressure conditions in said pipe. As particularly shown, a valve 14 is provided in a heat supply pipe 12 of the boiler and said valve is controlled by a suitable thermostat 15 which is inserted in the pipe 13 and is controlled by the temperature of the gas in said pipe. A back pressure valve 16 is interposed in the pipe 13 adjacent the jet compressor 6, said valve being shown as of the diaphragm

motor type and arranged to have its setting automatically controlled by the pressure behind it, whereby the pressure in the pipe 13 may be maintained at a constant value.

Fluid discharged from the jet compressor 6 is 5 conveyed to the condenser 7 through a pipe 17. The condenser 7 may be of any suitable type and is particularly shown as provided with condensing and accumulating chambers 18 and 19 respectively. A pipe 21 leads to the pump 8, 10 said pump being arranged to be power driven as by an electric motor 22. The liquid from the condenser chamber 19 is delivered from the pump to the boiler 5 through a pipe 23 to thereby complete the circuit which includes the 15 boiler.

It will now be noted that the present arrangement of apparatus is particularly adapted for cooling a circulating fluid. Accordingly, the evaporator 9 is shown as comprising a heat exchanger 24 to contain liquid refrigerant and the vapor thereof, and having therein a coil 25 connected by means of pipes 26 in a circuit (not otherwise shown) carrying the liquid to be cooled. 25 The evaporator 9 is arranged to be supplied with liquefied refrigerant from the condenser through a pipe 27, said pipe having an expansion valve 28 interposed therein, the latter being arranged for variable adjustment of its setting. A pipe 29 30 delivers gasified refrigerant from the evaporator 9 to the low pressure intake of the jet compressor 6. A back pressure valve 30 is interposed in the pipe 29, said valve being similar to the valve 16 whereby to automatically control the 35 discharge pressure of the gasified refrigerant to the jet compressor 6.

Referring to Figure 2, wherein is shown the structure of the element 6 which is hereinbefore referred to as a jet compressor, said element 40 is seen to be formed generally as an ejector, receives a gaseous stream of propelling fluid through the pipe 13, and discharges said stream as a jet from a nozzle 31 therefrom through a Venturi orifice 32 and so into the pipe 17. The 45 aforesaid propelling stream traverses a chamber 33 of the member 6 and said chamber is connected with the pipe 29, the flow of gaseous fluid from the pipe 29 and through the chamber 33 being induced by the aforesaid propelling 50 stream through the member 6. Since the action in the element 6 discharges the entrained refrigerant gas from the evaporator at a considerably increased pressure thereof and for discharge into the condenser at such increased pressure, said 55 element is understood to operate as a jet compressor and is therefore so referred to.

It will now be noted that the disclosed system and arrangement has been provided to fill a particular need in plants for refining mineral oils 60

and wherein the temperature of large quantities of products must be lowered below that obtainable with atmospherically cooled water. In such plants, an excess of reflux fluid is usually produced, and such a fluid is usually composed largely of propane or butane and is adapted for use as a refrigerant since the hydrocarbons propane and butane possess physical characteristics which permit the use of high suction pressures and low compression heads therewith, a fact which is of particular advantage when employing the jet compression principle in a refrigerating circuit. A further feature of interest in the use of propane as a refrigerant is the fact that propane has been found to be no less efficient in a refrigeration system than are ammonia or sulphur dioxide.

If pure propane is to be used as a refrigerant in the present system, the most desirable condition would be to vaporize the same in the evaporator 9 at an absolute pressure of 78 pounds per square inch, this resulting in a corresponding temperature of 40 degrees Fahrenheit. For insuring a most efficient further handling of this gasified refrigerant, it would be necessary that the same be compressed to an absolute pressure of 142.8 pounds per square inch for subsequent condensing at a temperature of not over 80 degrees Fahrenheit. To create the foregoing conditions and relations by means of the jet compressor 6 it is found that if the absolute boiler pressure is 500 pounds per square inch it would require the pressure flow of 2.02 pounds of propane through the jet compressor 31 to remove and compress one pound of propane vapor from the evaporator. It is noted that the figure 2.02 is numerically equal to the operative ratio of the jet compressor, said ratio being defined as that of the weight of propelling vapor to the weight of the vapor ejected and compressed by it. At a boiler pressure of 250 pounds per square inch the operative ratio of the jet compressor would be 20, while if the boiler pressure were 1000 pounds per square inch said operative ratio would only be 0.52. It will thus be clear that the efficiency of the present circuit is highest at high operating pressures therein, a preferred operating condition for the system being one in which the pressure at the boiler 5 would be between 500 and 1000 pounds per square inch absolute. Furthermore, with higher boiler pressures less heat is needed for vaporizing the propelling vapor, owing to the decrease of latent heat of vaporization with pressure. In determining the best boiler pressure it would obviously be necessary to operate at such a boiler pressure as will keep the boiler temperature well below the temperature of the heating fluid for the boiler. In view of the foregoing, it will be readily understood that provision of the pump 8 is essential in the present system.

Referring now to the composition of a reflux fluid which is produced in a refining plant of the type mentioned, a typical mixture would have the following composition:

Percent of the liquid volume	
Propane	59
Ethane	19
Iso-butane	10
Nor-butane	4
Methane	8

It is noted that the above reflux mixture would have a range of boiling points of about 75 Fahrenheit degrees at atmospheric pressure, this

mixture having an initial boiling point of minus 50 degrees Fahrenheit and a final boiling point of plus 25 degrees Fahrenheit. Said reflux mixture will operate very satisfactorily in the circuit of the present system, requiring only slight adjustment of the various valves, and would preferably be used about a refining plant where the reflux is at hand for use without alteration of its composition. The heating fluid circulated through the boiler might be a hotter product of the refining process, steam, or hot water, as such heated fluids may be most conveniently at hand; in the former case, an added economy of operation is effected.

In view of the foregoing description of the operation of the apparatus and the peculiar type of refrigerant which may be used therein, certain means of automatic control are provided to insure a proper performance of the operative cycle for which the present apparatus is designed. Thus, in order to insure a satisfactory heat exchange in the evaporator 9, a separator 34 is provided for preventing the passage of gasified refrigerant into the evaporator chamber 24. As particularly shown, the separator 34 provides a closed chamber 35 connected in the pipe 27 at the discharge side of the expansion valve 28, and further connected in the pipe 29 whereby the gasified refrigerant from the evaporator chamber 24 may flow through its upper portion. Since it is generally desirable that a predetermined level of liquid in the chamber 24 be maintained, a float control device 36 is provided in association with the separator 34, said device operative to control the setting of the expansion valve 28 for maintaining the desired liquid level in the evaporator and separator. It will be understood that the separator 34 functions to remove any gasified refrigerant resulting from the liquid discharge through the valve 28 whereby only liquefied refrigerant is delivered to the evaporator for evaporation by means of the heat emanated from the fluid in the coil 25.

It is also desirable that the liquid refrigerant be maintained at a fixed level in the boiler 5, and to that end a by-pass pipe 37 is provided connecting the pipe 23 with the pipe 17 whereby excess liquid refrigerant may be directly returned to the condenser 7. A normally closed valve 38 is interposed in the pipe 35 and said valve is arranged for control in accordance with the liquid level in the boiler through a float control device 39 which directly actuates the valve. In this manner, any tendency to an excessive liquid content in the boiler is automatically prevented.

A safety valve 41 is provided for the condenser. In the case where the refrigerant comprises a mixture of compounds having differing boiling points, a pressure controlled valve 42 may also be provided in an outlet pipe for the condenser whereby to permit the escape of any gaseous ingredients of the mixture which may not be liquefied under a particular operating condition of the apparatus. The valve 42 would, of course, open at a lower pressure than would the safety valve 41.

Means are also provided for maintaining the desired flow ratio at the jet compressor, or 70 ejector, 6. As particularly illustrated, said means comprises the provision of a diaphragm motor valve 44 in the pipe 23 which delivers liquid refrigerant from the pump to the boiler 5, and is controlled in terms of the flow rates 75

through the pipes 13 and 29 which lead to the ejector 6. The valve 44 is normally open to an intermediate degree and is arranged to be opened or closed to control the boiler feed for 5 counteracting any variation of the flow rate ratio from normal. Control of the valve 34 is arranged to be effected through the application of compressed air in its diaphragm chamber, said air conveyed to the valve through a pipe 45 10 connected with a compressed air source (not shown). An air valve 46 is interposed in the pipe 45, said valve being of a double diaphragm motor type and having valve-actuating diaphragms controlled by the differentials in pressure at opposite sides of orifice plates 47 and 48 15 interposed in the pipes 13 and 29 respectively. A constantly open needle valve 49 in the pipe 45, and at the discharge side of the valve 46, is operative to constantly relieve the pressure in the pipe 45 at an adjusted rate. By using orifice plates to have equal pressure differences for the desired flow rates in the respective pipes, the flow through the valve 46 may be held constant 20 as long as a proper flow ratio obtains in the pipes 13 and 29.

Should the flow ratio change from its desired normal, the air flow through the valve 46 will be automatically varied to appropriately change the operative air pressure at the valve 44 for 25 restoring said flow ratio to normal.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device 30 shown is merely illustrative, and that such changes may be made, when desired, as fall within the scope of the appended claims.

Having thus described my invention, I claim 35 as new and desire to secure by Letters Patent 45 of the United States the following:

1. In a continuously operable refrigeration circuit, a boiler, an ejector receiving a stream of gasified refrigerant from said boiler, a condenser receiving the discharge from said ejector, a 50 duct conducting condensate from said condenser back to said boiler, an evaporator comprising the cooling means of the circuit and directly receiving condensate from said condenser, means connecting said evaporator to said ejector whereby 55 the latter is arranged to remove gasified refrigerant from said evaporator, and means automatically operable in said duct in accordance with the quantity flow rates of gasified refrigerant from the boiler and evaporator to the 60 ejector to maintain the ratio of said flow rates at a constant and predetermined value.

2. In a continuously operable refrigeration system, a boiler and an ejector and a condenser connected in a continuous closed circuit, 65 said ejector receiving gasified refrigerant from said boiler, an evaporator comprising the cooling means of the system included in a branch circuit to receive liquefied refrigerant from the condenser and to deliver gasified refrigerant to 70 the ejector, and means operative in the con-

nnection between the condenser and boiler and in accordance with the flow rates of the streams to said ejector to automatically maintain a predetermined flow ratio between said streams.

3. In a continuously operable refrigeration 5 system, a boiler and an ejector and a condenser connected in a continuous closed circuit, said ejector receiving gasified refrigerant from said boiler, an evaporator comprising the cooling means of the system and included in a branch 10 circuit to receive liquefied refrigerant from the condenser and to deliver gasified refrigerant to the ejector, a motor valve controlling the flow of liquefied refrigerant from the condenser to the boiler, and means operative in joint accordance 15 with the flow rates of the streams of gasified refrigerant to said ejector to automatically determine the setting of said motor valve.

4. In a continuously operable refrigeration 20 system, a boiler and an ejector and a condenser connected in order in a closed circuit, said ejector receiving a propelling stream of gasified refrigerant from said boiler, means automatically operative to maintain constant temperature and pressure conditions in said propelling stream of 25 gasified refrigerant, a motor valve operative to control the flow of liquefied refrigerant from the condenser to the boiler, and means simultaneously coercive in accordance with the flow conditions in the said streams to the ejector to 30 control said valve for the maintaining a predetermined flow ratio between said streams.

5. In a continuously operable refrigeration 35 system, a boiler and an ejector and a condenser connected in a continuous closed circuit, said ejector receiving gasified refrigerant from said boiler, an evaporator comprising the cooling means of the system included in a branch 40 circuit to receive liquefied refrigerant from the condenser and to deliver gasified refrigerant to the ejector, and valve means operative in a connection of the first circuit and in joint accordance with the flow rates of the streams to said ejector to automatically maintain a predetermined flow ratio between said 45 streams.

6. In a continuously operable and closed refrigeration circuit, a boiler, an ejector, a duct 50 conducting a propelling stream of gasified refrigerant from said boiler to the ejector, a condenser receiving the discharge from said ejector and connected with said boiler for supplying liquid refrigerant thereto, an evaporator comprising the cooling means of the circuit and directly receiving liquid refrigerant from said 55 condenser, a duct connecting said evaporator to said ejector whereby the latter is operative to aspirate gasified refrigerant from said evaporator, back pressure valves independently operative in said ducts to automatically maintain 60 predetermined and constant operating pressures in the boiler and evaporator, and means operative in a boiler connection of the circuit and in accordance with the flow rates of the streams in said ducts to automatically maintain a predetermined flow ratio between said streams 65 whereby said ejector is arranged for operation as a jet compressor at a preferred said ratio for the refrigerant in the circuit.
